The ornamental design for a dual ended applicator with window, as shown and described.

DESCRIPTION

FIG. 1 is a front perspective view of a dual ended applicator with window showing one embodiment of our new design.

FIG. 2 is a top plan view, the bottom plan view being a mirror image thereof.

FIG. 3 is a front elevation view thereof.

FIG. 4 is a right end elevation view thereof.

FIG. 5 is a rear elevation view thereof; and,

FIG. 6 is a left end elevation view thereof.

The broken lines in the figures are for illustrative purposes only and form no part of the claimed design.
